UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,845**, dated September 2, 1873; application filed August 9, 1873.
[Term of Patent 3½ years.]

Y.

To all whom it may concern:

Be it known that I, FREDERICK WINK, of the city and county of Philadelphia, State of Pennsylvania, have invented a Design for Shawl-Pattern, of which the following is a specification:

The figure in the accompanying drawing clearly illustrates my design for a shawl-pattern, which consists of an arrangement of plain parallel stripes, bars, or ribs of different widths and shades or colors, the whole of the pattern being shown in the drawing, and the remainder being merely a repetition of that which appears.

The pattern may be viewed as though com-

posed of two main stripes, A and B, of which *x* and *y* are the centers and *z* the division-line.

Irrespective of the colors employed, I claim—

The design for a shawl-pattern, as described, and as represented in and by the accompanying drawing.

In testimony whereof I have signed my name to this specification in the presence of two subscribing witnesses.

FRED. WINK.

Witnesses:

CLINTON M. LATOURETTE,
LEWIS T. GODFREY.
